UNITED STATES PATENT OFFICE.

FRANCIS W. THAYER, OF DAYTON, OHIO.

MACHINE FOR CANCELING AND REGISTERING LETTERS.

SPECIFICATION forming part of Letters Patent No. 583,954, dated June 8, 1897.

Application filed September 4, 1896. Serial No. 604,907. (No model.)

To all whom it may concern:

Be it known that I, FRANCIS W. THAYER, a citizen of the United States, residing at Dayton, in the county of Montgomery and State of Ohio, have invented certain new and useful Improvements in Machines for Canceling and Registering Letters; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to improvements in letter or mail boxes.

The invention has for its object to provide a mailing-box having means for simultaneously canceling the stamp and stamping upon the envelop the name of the mailing-point, the date of mailing, and the time of collection, the entire operation being performed when the letter is delivered to the box, as will hereinafter be more fully described in connection with the accompanying drawings, of which—

Figures 1 and 2 are front and side elevations, respectively, of the box. Figs. 3 and 4 are front and side elevations, respectively, of the recording and timing mechanism removed from the box. Fig. 5 is a top view of the impression-lever detached. Figs. 6 and 7 are front and side elevations, respectively, of the cancelling-plate. Fig. 8 is a lower end view of the cancelling and printing plates assembled. Fig. 9 is a side elevation of the printing-plates. Fig. 10 is a view of the device for indicating the time of opening the box by the collector. Fig. 11 is the front of a letter as it appears after taken out of the box by the collector.

Referring in detail to the invention, similar reference-characters indicate corresponding parts in the several views.

1 designates the box or inclosing case, having an end door 2 and mailing-slots 3 and 4. The former is for the reception of letters exclusively, and adjacent to it is located the mechanism for canceling and stamping the letters as they are placed in the box. This mechanism is shown in Figs. 3 and 4, wherein 5 designates a frame in which are mounted

the journals of a roller 6 and the journals of an upper roller 7. The latter roller has springs 7' above its journals that apply pressure 55 thereto. The space between these rollers is sufficient to permit a letter to pass, and said space, when the rollers are in position, is in line with the slot 3.

8 is a gear-wheel on an end of roller 6, and 60 9 is a second gear that meshes therewith and drives roller 6. The gear 9 is driven in any suitable way, preferably by clock mechanism located in a convenient position, as per 10.

11 designates a canceling-plate, the lower 65 portion of which comes in contact with the stamp and cancels it. The portion 12 of said canceling-plate has an excess of weight to return the plates back to an operative position after the passage of each letter—that is to 70 say, when the plates are pushed in on their pivots by the passage of a letter the weight of the part 12 will return said plates to their former position with the type again in position to imprint.

75 13 is an integral or attached bar projecting at a right angle from the opposite end of the plate 11.

14, 14^a, and 14^b designate, respectively, type-bearing plates for imprinting the name of the 80 mailing-place, the date of mailing, and the time of collection. These plates occupy the space between the inner edge 11^a of the canceling-plate and the bar 13. The type are placed in an opening in the plates and are 85 maintained in an operative position by springs 15, that press them tightly together. 16 designates an ink-ribbon that is passed over the face of the plates and is secured in notches 17 in the edges of the plates. The 90 canceling and type plates are mounted on the end of an arbor 18, which is journaled in the supporting plate or frame 5. The openings for the journals are somewhat larger than said journals in order that the arbor may slightly 95 yield against the pressure of springs 19, that press downwardly against said journals and are mounted in the journal-openings.

20 designates a wire guide secured to a side of the frame 5 and projecting downwardly 100 and terminating parallel with the rollers. The horizontal part of this guide lies just above the opening between the rollers, and its function is to direct downwardly the smaller

envelops that do not reach the entire width of the rollers and might have a tendency to project upward at one end when the letter is inserted in the slot 3.

- 5 21 designates an angular wire that is pivoted on the inside of the front of the box. One end 22 of this wire lies in the path of a lug 23 on the lower end of the type-plate 14, and the other end 24 is pointed and projects 10 at a right angle in contact with the time-dial of the clock, as shown in Fig. 3. The dial is constructed of any material susceptible of an impression, such as pasteboard, and a new one is placed on the clock on each collection 15 of the mail. The movement of the type-plates caused by the insertion of a letter will actuate the wire 21 and cause the end 24 to make a short indentation on the dial, showing each time that a letter has been passed into the box.
- 20 In Figs. 1 and 10 there is shown a device for indicating when the box has been opened by the collector and consisting of a lever 25, having its fulcrum at 26 on a convenient part. The outer end 27 of this lever rests on 25 a pin 28 on the interior of the door 2, while the inner end 29 is in close proximity to the face of the time-dial. As said door is opened the movement of the pin 28 raises said lever on its fulcrum and causes the end 29 to impact with the dial and make an indentation thereon. The closing of the door will return 30 said lever to its normal position. The type indicating the place where the letters are mailed are permanent. Those indicating the 35 date and time are changed at the proper times by the collector—the former once a day, the latter after each collection is made.

In Fig. 3, 30 designates a letter passing below the plates and as having moved to a 40 position where the type-plates are making an

impression. The plates have moved from the position in dotted lines. When the letter shall have passed entirely through and is deposited in the box, the plates will resume their former positions with the canceling portion 45 of the plate over the roller 6. The weight of said canceling portion of the plate is sufficient to cause the plates to return until the said portion reaches the center of gravity, which is above the roller 6. 50

Having described my invention, I claim—

1. In a mail-box, the combination of rollers mounted on the interior of said box adjacent to the slot through which the letters are inserted, a canceling-plate, and a series of type-plates mounted above said rollers with their impression ends occupying the same plane or approximately the same plane as the opening between the rollers, and means for rotating one of said rollers to feed the letter between 60 it and the said canceling and type plates, substantially as shown and described.
2. In a mail-box, the combination with a supporting-frame located on the interior of the mail-box, of rollers mounted in said frame, a canceling-plate, and a series of type-bearing plates mounted above one end of one of said rollers, a loosely-mounted arbor parallel with said rollers upon which said plates are mounted, a guide attached to said frame to 65 direct the letters to the rollers, and clock mechanism for rotating one of said rollers, substantially as shown and described.

In testimony whereof I affix my signature in presence of two witnesses.

FRANCIS W. THAYER.
